ATTORNEY

UNITED STATES PATENT OFFICE

FRANCESCO MANGIAMELI, OF DUSSELDORF, GERMANY

APPARATUS FOR MIXING GASES

Application filed October 8, 1931, Serial No. 567,654, and in Germany August 7, 1931.

The invention relates to apparatus for effecting the mixture of gases in any desired proportions, for use in burners, blow torches or the like, and comprises a compound valve device connected to the sources of supply of the gases and to a mixing chamber, said valve device including a casing having a cylindrical bore provided with parallel, peripheral series of discharge ports communicating with the mixing chamber and a valve plug in the casing operative to uncover any desired number of ports in one series and simultaneously close a like number of ports in the other series; the apparatus preferably being associated with a novel means for balancing or equalizing the pressures of the gases in advance of the valve mechanism.

The invention is illustrated in the accompanying drawing, in which:—

Fig. 1 is a sectional elevation of the valve device and mixing chamber.

Figs. 2 and 3 are sections on lines A—B and C—D, respectively, of Fig. 1.

Fig. 4 is a sectional elevation of the pressure equalizing apparatus with the valve associated therewith shown in elevation.

Referring to Figs. 1 to 3 of the drawing, *a* indicates the valve casing proper, which is provided with a cylindrical bore terminating in end chambers *c* and *d*, into which open supply ducts *a* and *b*, respectively, which ducts are in communication with the respective supplies of the gases to be mixed. The cylindrical bore of the casing is provided with two peripheral series of discharge ports *f* and *g*, respectively, each series extending through an arc of substantially 180° and communicating with discharge ducts *h* and *h'* formed in the body of the casing and communicating with a common mixing chamber *h''*, which may be formed as an integral part of the valve casing, the outlets of the discharge ducts *h* and *h'* being closed against reverse flow by check valves *m* and *n*, respectively, the mixing chamber having a discharge outlet *x* adapted to be connected with the conduit leading to the burners, blow torches or the like. Fitting within the cylindrical bore of the casing is a valve plug or member *e*, the main body portion of which

is cylindrical and having semi-cylindrical end sections on opposite sides adapted to be moved into and out of registry with the respective series of ports. The valve member *e* is provided with a stem passing through the packing gland or stuffing box on one end of the casing, said stem being provided with an operating hand wheel *i*, which may be conveniently marked with a scale to indicate the relative proportions of the gases delivered by the valve to the mixing chamber, said scale cooperating with a fixed pointer or index *l*.

The ports of each series *f* and *g* are disposed at regular intervals and the ports of the respective series are made of such predetermined diameters as to insure passage of equal volumes of the gases through each single port, the diametrical dimensions of the ports being determined by the densities of the respective gases.

By the particular construction and arrangement of the elements of the valve mechanism, as described, it will be seen that, when the valve member *e* is rotated, the ports of one series will be successively closed, while the ports of the other series will be simultaneously opened and, as each port in both series is designed to discharge the same volume of gas, the relative proportions of the gases delivered to the mixing chamber may be accurately regulated. As illustrated in Fig. 1, all of the ports *f* are open, while all of the ports *g* are closed, so that only the gas reaching the valve device by way of the duct *a* will be delivered to the mixing chamber. By turning the valve plug *e* to close one port *f*, the same movement of the valve uncovers one port *g*. Continued rotation of the valve will effect the opening of the ports in the respective series in the order of 8—2, 7—3, 6—4, etc., so that any desired proportions of the respective gases may be delivered to the mixing chamber *h''*.

As hereinbefore stated, it is desirable that the gases to be mixed be supplied to the regulating valve and the mixing chamber at substantially the same pressures and, to this end, the apparatus is associated with a pressure regulating device, which may conveniently take the form illustrated in Fig. 4, compris-

ing two tank sections *o* and *p* connected at their bottoms and adapted to receive a body of liquid, such as water, which rises to the level of the gauge cocks *q* and *q'*, respectively, the upper portions of the tanks being connected by pipes or conduits *a'* and *b'* to the inlet ports *a* and *b*, respectively, of the valve casing *a²*. The upper portions of the tank sections are also provided with pressure gauges *i*, *i* to indicate the pressure of the gases in the respective tank sections. The inlets to the respective tank sections are in the form of dip pipes *r* and *s*, the lower ends of which are submerged in the liquid in the respective tank sections to such depths as will insure the pressures of the gases in the upper portions of the tanks being equal and, in order to accurately balance such pressures, at least one of the inlet pipes *r* or *s* is perpendicularly adjustable in the tank, so as to regulate the relative depths of immersion of the pipe ends.

While the valve mechanism has been illustrated in its preferred form as involving a single valve body or plug, it will be apparent that a single plug may be substituted by two plugs, one to control each series of circumferential ports and each provided with a separate stem and operating head, so that they may be separately actuated to control the relative proportion of the gases delivered to the mixing chamber.

What I claim is:

1. A mixing device for gases, comprising a valve casing having inlet and discharge ducts for the respective gases and two peripheral series of wall ports communicating with the respective discharge ducts, and a valve in said casing adapted to uncover the ports of one series successively and simultaneously close a like number of ports in the other series.
2. A mixing device for gases as described in claim 1, in which the casing has a cylindrical bore and the valve is a cylindrical plug fitting the bore having semi-cylindrical end sections on opposite sides adapted to be moved into and out of registry with the respective series of ports.
3. A mixing device for gases, comprising a valve casing having inlet and discharge ducts for the respective gases and two peripheral series of wall ports communicating with the respective discharge ducts, a valve in said casing adapted to uncover the ports of one series successively and simultaneously close a like number of ports in the other series, and a mixing chamber into which the discharge ducts open.
4. A mixing device for gases, comprising a valve casing having inlet and discharge ducts for the respective gases and two peripheral series of wall ports communicating with the respective discharge ducts, a valve in said casing adapted to uncover the ports

of one series successively and simultaneously close a like number of ports in the other series, a mixing chamber into which the discharge ducts open, and check valves to prevent back flow from said mixing chamber to the discharge ducts.

5. A mixing device as described in claim 1, in which the wall ports of each series are made of such diameters as to insure the flow of equal volumes of gas through each port.
